CABOB GRILLE

James Headberg, 10250 SW. 156 St., Miami, Fla.

Filed Oct. 16, 1964, Ser. No. 82,195

Term of patent 14 years

(Cl. D81—10)

FIG. 1

FIG. 2

FIG. 3

FIG. 1 is a side elevation of a cabob grille showing my new design.

FIG. 2 is a top plan view thereof.

FIG. 3 is a cross sectional view taken through section line 3—3, FIG. 2.

The skewers and food shown on one of said skewers are included for illustrative purposes only.

I claim:

The ornamental design for a cabob grille, as shown and described.
